(57) **CLAIM**

The ornamental design for a display screen with graphical user interface, as shown and described.

DESCRIPTION

FIG. 1 is a front view of a first embodiment of the display screen with graphical user interface;

FIG. 2 is a front view of a second embodiment of the display screen with graphical user interface; and,

FIG. 3 is a front view of a third embodiment of the display screen with graphical user interface.

The broken lines shown in the drawings are included for purposes of illustrating environment or portions of the display screen with graphical user interface and form no part of the claimed design.

1 Claim, 3 Drawing Sheets
